UNITED STATES PATENT OFFICE.

THOMAS CLARKSON, OF CHELMSFORD, ENGLAND.

REGULATION OF LIQUID-FUEL BURNERS.

No. 825,892.

Specification of Letters Patent.

Patented July 17, 1906.

Application filed August 22, 1904. Serial No. 221,776.

To all whom it may concern:

Be it known that I, THOMAS CLARKSON, a subject of the King of England, residing at Chelmsford, England, have invented certain new and useful Improvements in or Relating 5 to the Regulation of Liquid-Fuel Burners, of which the following is a specification.

This invention relates to the regulation of liquid-fuel burners, and has for its object to 10 enable the regulation to be effected automatically and also when desired by hand, the latter being possible without in any way affecting the automatic mechanism.

The mechanism forming the subject of this 15 invention is intended chiefly for use with liquid-fuel burners in which both the size of the flame issuing from the burner and the amount of fuel are simultaneously regulated; but the invention is also applicable to other forms of 20 burners.

According to the present invention the control of the simultaneous movement is effected 25 automatically by the pressure of steam in the generator heated by the burner, this steam acting upon a piston against the pressure of an adjustable spring. Between the piston and its rod and the burner-regulating mechanism is disposed a direct but yielding connection, the arrangement being such that 30 when the pressure of steam forces up the piston against the action of the spring the movement is imparted to the mechanism controlling the burner, and on account of the yielding connection no jamming can occur, and, 35 further, the burner-controlling mechanism may be moved by hand without affecting the automatic movement of the piston.

In order to enable the burner to be controlled by hand, the hand-operated device is 40 connected to the controlling mechanism and a yielding connection is disposed between the hand-operated device and the automatic regulator.

The details of the above combined automatic and hand controlling mechanism may 45 be varied in accordance with requirements, and the invention will be described in its preferred form as applied to a burner wherein there is employed a needle for controlling the 50 fuel-orifice and a cap which controls the size of the flame, these two parts being moved simultaneously.

Figure 1 is an elevation, partly in section, of a preferred form of burner having the present invention applied thereto. Fig. 2 is an 55 end elevation, partly in section, of the same.

A is the yielding connection between the automatic controlling mechanism B and the burner D, and C is the hand controlling mechanism. 60

The burner D has a fuel-chamber D', at one end of which is situated the fuel-inlet nozzle D², the opening of the nozzle being controlled by a needle D³, to which is attached a spring D⁴. At the opposite end of the fuel-chamber is disposed the nozzle D⁹, through which the combustible mixture issues, the outlet being controlled by a cap D⁸, mounted on a spindle D⁷ and controlled by a lever D⁶. The fuel is heated by the flame issuing from 70 the nozzle D⁹, the coil D⁵, through which the fuel passes to the nozzle D², being situated above the flame-orifice, as shown. The lever D⁶ is pivoted at d to a stationary support and has a forked end d' engaging with a collar on 75 the end of the spindle D⁷, to which the cap D⁸ is attached.

The automatic controlling device B is in the form of a piston-regulator, consisting of a cylinder B', in which is situated a piston B², 80 the rod of which is connected to a piece B⁶, having a projection of semispherical form which rests in a groove or socket in the piston B². Beneath the piston B² is attached an elastic or flexible cup B⁴, through which extends a stud b, and the cup B⁴ is retained in position by a nut b' on the stud b and the washer b². Between the member B⁶ and cross-piece B⁸, through which the piston-rod B³ passes, is disposed a coil-spring B⁷, against 90 which the pressure in the chamber B⁹, which is situated between the cup B⁴ and the lower end of the cylinder, has to act to operate the controlling mechanism and vary the flame. 95

The automatic controlling device B is connected to the nozzle-controlling mechanism and also to the flame-controlling mechanism, so as to simultaneously vary both the supply of fuel to the burner and the quantity of combustible mixture, and therefore the size of the 100 flame issuing therefrom.

The piston B² is acted upon by the steam-pressure which enters the chamber B⁹ by the pipe B¹⁰. The upper end of the rod B³ passes

- through an opening in the cross-piece B¹¹, which is connected by links B¹² or other appropriate mechanism to the lever D⁶ and also by suitable connections to the needle D³.
- 5 When pressure of steam forces up the piston against the action of the spring B⁷, the movement is imparted to the mechanism controlling the burner through the cross-piece B¹¹ and side links B¹². The connection between
- 10 the piston-rod B³ and the cross-piece B¹¹ is direct, but yielding, so that no jamming can take place nor the mechanism be strained should the steam-pressure on the piston be higher than is necessary to close the fuel and
- 15 flame openings. This yielding connection is of metal and in the form shown comprises two springs A' A², one end of each of which bears against a sleeve B¹⁴, having a central enlargement between which and the ends of
- 20 the springs are disposed collars A³ A⁴. The opposite ends of the springs bear, respectively, against the collars or nuts A⁵ A⁶ on the piston-rod, and these nuts also hold the sleeve B¹⁴ in position and cause it to move with the piston-rod. The enlargement on the sleeve B¹⁴ lies within an opening or eye in the cross-piece B¹¹, so that when the piston-rod rises or falls it carries with it the cross-piece B¹¹, which, as above stated, is connected with the
- 25 30 links B¹², attached to the burner-controlling mechanism.

When steam enters the cylinder of the regulator below the piston, the rod B³ is forced upward, causing the nut A⁵ thereon to compress the spring A' against the washer A⁴, which bearing on the bridge-piece B¹¹ raises this and causes the links B¹² to act on the burner-controlled mechanism. Similarly, when the pressure is withdrawn the piston-rod descends under the action of the spring B⁷, causing the nut A⁶ on the rod B³ to compress the spring A² against the nut A³, forcing the bridge-piece B¹¹ down and again causing the links to act on the burner-controlled mechanism. The same operation takes place when the lever C' is operated by hand.

- In order to enable the burner to be controlled by hand, suitable hand controlling mechanism is attached to the side links B¹².
- 50 This hand controlling mechanism C comprises conveniently a lever C', pivoted at c to a notched quadrant C³, over which it can move and with which a spring or drop catch C² on the lever C' engages. At its lower end the lever C' has a crank C⁴, to which is pivoted one end of a link C⁵, the other end of which is pivoted to an extension of the links B¹², which in turn are connected at their upper ends by a bar B¹³.
- 60 The yielding connection between the side links and the piston of the regulator allows the hand controlling mechanism to be operated independently of the automatic con-

trolling mechanism, as it is only necessary when it is desired to raise or lower the flame by hand to overcome the pressure of one of the springs A' A², which maintain the cross-piece B¹¹ in its normal position. The springs A' A² also serve to return the hand-lever C' after it has been operated to the position which it should occupy to accord with the automatic controlling mechanism.

It will thus be seen that the hand mechanism while allowing the burner to be controlled also serves as an indicator of the movement of the automatic controlling mechanism. It is also possible by means of the hand control to move the needle and cap of the burner, and thus insure their being free and in working order at all times. The hand-operated mechanism can be disconnected to permit the automatic regulator to act freely by disengaging the catch C² from the quadrant C³.

The hand-operated lever C' when free to move with the hand-operated regulator may be employed as an indicator, since by placing marks on the quadrant the position of the needle D³ and cap D⁸ may be ascertained and also the steam-pressure in the cylinder B'.

As above stated, the constructional details may be varied, the principal features being the fact that the two methods of controlling the burner while capable of separate operation will yet work jointly, and one is an indication of the movements of the other.

What I claim as my invention, and desire to secure by Letters Patent, is

1. In mechanism for controlling a liquid-fuel burner, the combination with mechanism for varying the flame by controlling the supply of fuel to the burner and altering the dimensions of the burner-outlet, of a hand-operated device directly connected to the control mechanism, a piston-regulator operated by the pressure of steam in the generator heated by the burner, and a yielding connection between the piston-regulator and the burner-control mechanism.

2. In mechanism for controlling a liquid-fuel burner, the combination with mechanism for varying the flame by controlling the supply of fuel to the burner and altering the dimensions of the burner-outlet, of a hand-operated device directly connected to the control mechanism, a piston-regulator operated by the pressure of steam in the generator heated by the burner, a yielding connection between the piston-regulator and some point in the hand control device, and a lock for the hand control device.

3. In mechanism for controlling a liquid-fuel burner, the combination with mechanism for varying the flame by controlling the supply of fuel to the burner and altering the dimensions of the burner-outlet, of an automatically-operated piston-regulator, a hand-

operated control device, links connecting the latter with the burner-controlling mechanism, a cross-piece connecting the links and through which the piston-rod of the regulator 5 passes, springs disposed on the piston-rod on opposite sides of the cross-piece, and adjustable stops on the piston-rod confining the springs.

In testimony whereof I have signed my name to this specification in the presence of 10 two subscribing witnesses.

THOMAS CLARKSON.
